T. R. WOLLASTON,
GAS PRODUCER.
APPLICATION FILED JAN. 19, 1918.

1,315,269.

Patented Sept. 9, 1919.

Inventor
Thomas Roland Wollaston
per Arthur Gaedt
Attorney.

UNITED STATES PATENT OFFICE.

THOMAS ROLAND WOLLASTON, OF MANCHESTER, ENGLAND.

GAS-PRODUCER.

1,315,269.

Specification of Letters Patent. Patented Sept. 9, 1919.

Application filed January 19, 1918. Serial No. 212,650.

To all whom it may concern:

Be it known that I, THOMAS ROLAND WOLLASTON, a subject of the King of Great Britain, residing at 26 Corporation street, Manchester, England, have invented certain new and useful improvements in Gas-Producers, of which the following is a specification.

This invention relates to improvements in apparatus for generating producer gas, and 10 of the character set forth and illustrated in the specification of my prior British Patent No. 12400 of 1914, in which the fuel bed is annular in form by reason of a central or eccentrically arranged core or dome within, 15 through which the blast is suitably directed prior to its introduction to the fuel zone and, in becoming superheated, abstracts heat from the fuel bed.

In carrying out this invention, I provide 20 suitably located in the pipe or passage for the blast, one or more jets or spray nozzles, of convenient form, for water or tar liquid, or both, so that sprays of water or tar may become vaporized and intimately associated 25 with the blast at or about the position at which the same meet, and in their course through the core aforesaid become vaporized or brought to a finely divided condition or fog, and superheated, previous to introduction to the combustion zone of the producer.

With reference to the accompanying drawings, Figure 1 is a sectional elevation of the main portion of a gas producer showing a 35 central hollow core in connection with the grate, and an internal blast pipe as described in the specification of my former patent referred to herein said core being provided with liquid supply and atomizing means arranged according to my present invention.

Figs. 2 and 3 show sectional elevations of modifications of the invention.

With reference to Fig. 1, *a, a*, are the walls of the producer which is situated above 45 a water trough *b* and provided with a fuel grate *c*. Through this grate extends a blast pipe *d* toward the upper end *e* of a hollow core *f* about said blast pipe, and according to my former patent before named.

50 In addition to the means already described, and according to my present invention, I provide means for introducing water or tar liquid, or both, in a finely divided or atomized condition, within the passage or dome through which the blast passes.

In Fig. 1 the means consist of a depending pipe *h* provided with a suitably perforated nozzle *h'*, and so as to operate as an atomizer, through which pipe water or tar liquid is ejected for the purpose stated. In 60 Fig. 2 a number of depending pipes *h* fitted with nozzles *h'* are illustrated. The core *f* is extended from the grate to the top of the producer, or part from which the pipes *h* project. The atomizing means may consist 65 of any well known baffle character, such as that which has a nozzle within which and near to the end thereof there are a pair of baffles or disks, parallel with each other, or thereabout, each disk provided with a small 70 aperture, the two apertures not being opposite to each other.

It will be seen that on the emergence of the water or tar from the pipes *h*, it will mingle with the blast from the pipe *d* and 75 become vaporized and superheated. On its passing down the outside of the blast pipe *d* and between it and the core *f*, further heat is abstracted from the hot zone of the producer as compared with that abstracted 80 with the use of the blast alone, since by the means described, the degree of saturation of the blast is raised; added to which, when injected tar is used, the latter is partly converted to fixed gas.

The combination blast eventually issues 85 from the grate *c* into the combustion zone of the producer. With reference to Fig. 2, the passage for the blast or interior of the core *f* is shown provided with several spray pipes 90 *h* and to operate as atomizers, projecting through the top cover of said core, which core is of that character which extends to the upper part of the producer.

It is obvious that all the pipes *h* could be 95 supplied with water for spraying purposes, or could be supplied with tar liquid, or partly the one and partly the other.

In any case the sprayed or finely divided vapor is capable of more readily mixing with 100 the ejected contents of the blast pipe *d*.

With reference to Fig. 3, a similar kind of core is shown to that illustrated in Fig. 2, but the blast pipe *d* does not extend so far up the same. The remainder of the upper 105 part of said core is taken up by a coil *k*, having perforations *m* in its lower portion through which coil water or tar liquid may be forced or passed so as to emerge near to the outlet for the blast pipe *d*. The lower 110

portion of said coil referred to, would be provided internally as an atomizer as already described or otherwise be capable of acting as an atomizer.

5 I claim:—

In a gas producer with a grate, and in combination, depending liquid supply and atomizing means within a rigidly mounted

hollow core extending from the grate of said producer, and a blast pipe with extremity 10 external to and opposed to said depending means, within said core, substantially as herein set forth.

In testimony whereof I have affixed my signature.

THOMAS ROLAND WOLLASTON.
